UNITED STATES PATENT OFFICE.

ALBION KNOWLTON, OF BOSTON, MASSACHUSETTS, ASSIGNOR TO THE CORRUGATED WIRE FASTENING COMPANY, OF HARTFORD, CONNECTICUT.

SOLE-NAILING MACHINE.

SPECIFICATION forming part of Letters Patent No. 240,254, dated April 19, 1881.

Application filed June 2, 1880. (No model.)

To all whom it may concern:

Be it known that I, ALBION KNOWLTON, of Boston, in the county of Suffolk and State of Massachusetts, have invented an Improved Sole-Nailing Machine, of which the following is a full, clear, concise, and exact description, reference being had to the accompanying drawings, making a part hereof.

Swinging-head pegging-machines have been widely used for many years for pegging boots and shoes with wood pegs cut from a strip of peg-wood, and the main object of my invention is to adapt these machines for driving wire fastenings instead of wooden pegs; and my invention consists, mainly, in the combination of a mechanism for feeding the wire, and a mechanism for cutting off the wire fastenings and presenting them properly to the driver with a swinging head carrying the driver-bar and shoe-feed.

In the drawings, Figure 1 is a side elevation of the upper part of one of these pegging-machines with my appliances in place of those for holding, feeding, and cutting the peg-wood. Fig. 2 is a front view; Fig. 3, the same with the face-plate removed. Fig. 4 is a perspective enlarged, showing the principal changes to adapt the machine for driving pegs of wire instead of pegs cut from a strip of peg-wood. Figs. 5, 6, 7, and 8 are details showing the principal parts in the altered machine.

The parts marked with numerals are all in the machine, and therefore need no description.

The parts new with me are plate A, the cutter B, its spring C, the throat and cutter-carrier D, the wire-guide tube F, and the wire-feed mechanism.

The plate A is firmly fastened to the swinging-head 6, and carries a stud upon which the cutter B is journaled. The spring C (see Figs. 1 and 8) acts to keep the cutter B against its stop b, the hole b² through the front end of the cutter being in line with the hole d through the throat and cutter-carrier D when the front end of B is against its stop b, so that the wire fed down through the guide-tube F will pass into the hole b² in B. The throat and cutter-carrier D is also secured to the swinging head 6,

the driver entering the hole d' and passing 50 through the hole d² when driving the peg. The guide-tube F is secured to the face-plate 7, which is fast to the swinging head 6, and arranged so that it opens into the hole d of the throat and cutter-carrier D. The wire-feed 55 wheels f f' are also secured to the face-plate 7. One of them, f', is provided with a ratchet, which is worked by a spring-pawl carried by the radius-bar f², and this bar is actuated by the slide f³, which slides in ways f⁴ attached 60 to the face-plate. This slide is actuated by the small cam f⁵, attached to the main cam 4 of the machine.

The operation is as follows: In Fig. 2 of the drawings the swinging head is shown in 65 its position just after the shoe has been fed. The driver is raised by the main cam 4, and the slide f³ is raised by the passage of its cam f⁶ under the wrist f⁶. Its upward motion raises the radius-bar f², which is suitably connected 70 with slide f³, and through the spring-pawl and ratchet turns the feed-wheel f', the throw of the feed-wheel f' depending upon the extent of motion of slide f³, the length of wire pegs being regulated at will by the eccentric-stop f⁷, 75 which acts as a stop to slide f³, as clearly shown in Fig. 2, the pegs being longest when slide f³ is allowed to descend as low as the eccentric f⁷ will permit. A spring, f⁸, is used to depress slide f³. The wire is fed down through tube 80 F through hole d into the hole b². As the swinging head swings back the friction-roll b' on cutter B is borne against the frame of the machine, and the hole b² thereby carried under hole d', cutting off a wire peg and carrying 85 it under hole d' and the driver. The driver and awl then descend and the head swings forward again to feed the shoe.

By the use of my devices this class of machines are converted at small expense into 90 wire-peg-driving machines.

I have shown only those parts of the pegging-machine necessary for the full understanding of the parts devised by me. The parts not shown are well understood by all skilled in 95 the art.

What I claim as my invention is—

1. In combination with the swinging head

6, the cutter B, operated to cut and carry the wire peg by the motion of the swinging head, substantially as described.

2. The mechanism for feeding the wire, consisting of feed-slide f^3 , radius-bar f^2 , wire-feed wheels f^4 , and feed-adjusting stop f^7 , arranged and combined together as described, whereby the length of wire fed can be varied by increasing or diminishing the downward motion of the feed-slide by means of stop f^7 .

3. The combination of cutter B, the throat and cutter-carrier D, guide-tube F, and wire-feed mechanism with the driver 9 and swing-head 6 of the pegging-machine, substantially as described.

4. The combination, with the swinging head carrying the driver and shoe-feeding mechanism, of the mechanism for feeding, cutting, and carrying the wire, substantially as described.

5. The combination, with the swinging head carrying the driver and shoe-feeding mechanism, of plate A, cutter B, journaled on the stud of plate A, its spring C, throat and cutter-carrier D, guide-tube F, and wire-feed mechanism, substantially as described.

ALBION KNOWLTON.
